CONTAINER HANDLING EQUIPMENT

John K. Bruce, Pasadena, and Thomas H. Davis, Alhambra, Calif., assignors to Bruce Engineering Corporation, San Francisco, Calif., a corporation of California

Application April 3, 1950, Serial No. 153,724

21 Claims. (Cl. 214—304)

1

This invention relates to materials handling equipment and more particularly, to apparatus for removing containers from shipping cartons.

In many industries, as for example, breweries, empty cans are received from the manufacturer in unsealed flap-covered cartons, generally containing about two dozen cans to the carton. It is, of course, necessary before these cans are filled, sealed, etc., to remove them from the cartons and deposit them on a conveyor line to the several operations. At present empty cans are removed from shipping cartons by hand, there being no apparatus available capable of opening the unsealed carton, extracting the cans therefrom, and placing the cans and empty carton on separate conveyors. When can consumption is large, the labor involved is appreciable. Moreover, the manual operation is inconsistent with the remainder of the filling, sealing, labelling and packaging stages, all of which are carried out in automatic machines. One Los Angeles brewery fills, seals, etc., approximately 120,000 cans per day, all automatically, but these cans are removed from the shipping carton by hand.

We have now developed apparatus capable of receiving such unsealed cartons, opening both the side and end flaps, extracting the exposed cans and depositing the cans on a conveyor, slide or other delivery means in a sequence of steps without damaging either the cans or the cartons. This latter feature is important since the same cartons are conventionally reused to ship the filled cans. The apparatus is capable of receiving the cartons in a continuous stream and performs the different operations sequentially on a series of cartons. Thus, as the cans are removed from one carton, the end flaps of the next succeeding carton are being opened and the side flaps of a third carton are being opened.

Whereas the apparatus of the invention is hereinafter particularly described for use in removing empty cans from an unsealed carton, it is not so limited. It may be used to remove any metallic containers, whether empty or full, from cartons which have not been sealed or which have been unsealed prior to introduction into the apparatus. The apparatus of the invention is capable of operating at substantially any throughput with rates of thirty cartons per minute, or even higher being entirely practical. In the case of beer cans, this rate represents 720 cans per minute. The above-mentioned brewery could replace manual labor with a single machine operating at the rate of eleven cartons per minute for less than eight hours.

2

The apparatus of the invention comprises a conveyor for the container-filled cartons, means operable to fold the side flaps of the cartons outwardly therefrom, separate means for folding the end flaps outwardly from the cartons and means for removing the cans from the cartons and depositing them outside the cartons, the several means being arranged to operate in sequence in the order named on each carton as it is carried by the conveyor.

In addition to providing improved means for opening the side flaps of a carton, the invention, as a particular feature, provides means for opening the end flaps of such a carton without altering the direction of travel or the orientation of the carton with respect to the conveyor. Presently existing means for opening cartons includes spaced pairs of plows arranged above cooperating conveyors, the first pair serving to fold the side flaps away from the top of the carton and the second pair engaging the end flaps after the direction of travel of the carton has been changed by passing from one conveyor to the adjoining conveyor arranged transversely with respect to the first conveyor. Alternatively the two pairs of plows are spaced from each other above a single conveyor and means are provided intermediate the pairs of plows to rotate the cartons through a 90° arc to orient the ends of the carton parallel instead of transverse to the direction of travel.

In the present apparatus, entirely different means is employed to open the end flaps of the carton which does not require any rotation of the carton or any change in its direction of travel. Briefly, this means comprises spaced traveling fingers which are caused to move intermittently above the carton at a rate in excess of the rate of travel of the carton. The fingers in traveling across the top of the carton are arranged to pivot on an axis transverse to their direction of travel in such a manner as to lift first one and then the other of the end flaps away from the carton. The movement of the fingers is synchronized with the travel of the cartons on the conveyor by means hereinafter detailed so that the flow of cartons is uninterrupted.

Another feature of the invention is the means for removing the cans from the boxes which comprises a large magnet, which may be either a permanent magnet or an electromagnet, disposed above the path of the opened cartons. A conveyor belt is caused to travel across the lower face of the magnet. As an open carton passes into the field of the magnet, the cans are held against the magnet while the carton is allowed to drop onto

a lower conveyor. The cans travel across the face of the magnet on the conveyor belt. As the conveyor belt travels beyond the field of the magnet, the cans adhering thereto are fed onto a discharge conveyor which carries them out of the apparatus.

The invention will be more clearly understood with reference to the accompanying drawing in which:

Fig. 1 is a longitudinal sectional elevation of apparatus in accordance with the invention;

Fig. 2 is a horizontal section taken on the line 2-2 of Fig. 1;

Fig. 2A is a section taken on the line 2A-2A of Fig. 2;

Fig. 3 is a transverse sectional elevation taken on the line 3-3 of Fig. 2;

Fig. 4 is a transverse sectional elevation taken on the line 4-4 of Fig. 2;

Fig. 5 is a sectional elevation taken on the line 5-5 of Fig. 4 showing the end flap opening mechanism at one point in its cycle;

Fig. 6 is a vertical section taken on the line 6-6 of Fig. 4 and showing the orientation of the timing mechanism at the stage in the cycle represented by Fig. 5;

Fig. 7 is a sectional elevation identical to Fig. 5 showing a different stage in the cycle of the end flap opening mechanism; and

Fig. 8 is a sectional elevation corresponding to Fig. 6 and showing the timing mechanism position at the stage in the cycle represented by Fig. 7.

Referring to the drawing and particularly Figs. 1 and 2, the apparatus includes a unitary supporting framework and housing 10, provided with a base 10A, side panels 10B, 10C, and a substantially enclosed motor housing 10D. The framework is adapted to rest on or be bolted to the floor or a raised platform and is internally braced so as not to require external support. A conveyor 12 is mounted horizontally in the framework and includes a pair of chains 12A, 12B carried over sprockets 13, 14 mounted on shafts 13A, 14A respectively, journaled through sides 10B, 10C of the housing.

A single power source is employed to operate the entire mechanism including conveyor 12. A motor 15 is mounted in the motor housing 10D and is connected through a speed reducer 16 by means of suitable belts and pulleys to a master drive pulley 18 also mounted in the motor housing 10D. The pulley 18 is mounted on a shaft 18A which also carries a sprocket 18B. A sprocket 20 is mounted beneath the motor housing 10D on a shaft 20A journaled through the framework sides and a chain 19 connects the sprockets 18B and 20. A second sprocket 20B is mounted on the shaft 20A and is connected by a chain 21 (shown in dotted lines in Fig. 1) to a sprocket 14B (Fig. 2) mounted on shaft 14A which also carries conveyor sprockets 14.

Cartons are delivered to the end of conveyor 12 by means of an auxiliary conveyor 26 traveling at a slower speed than conveyor 12.

Stationary detents 27, 27A are mounted to the framework on opposite sides of the conveyor 12 and adjacent the end of the conveyor. The detents 27, 27A project into the path of the cartons delivered from conveyor 26 preventing access to conveyor 12.

The conveyor 12 which conveniently comprises a pair of parallel chains 12A, 12B, carries a number of spaced pusher bars 28, 28A, 28B, 28C mounted across the chains 12A, 12B. When one

of the pusher bars engages under a carton held by detents 27, 27A, as for example, a carton 30 as shown in the drawing, it lifts the carton over the detent and slides under the carton to engage against the back lower edge of a preceding carton. A spring detent 32 spaced from the detent 27 retains each successive carton until the carton is engaged and forced past the spring detent by one of the pusher bars. Briefly, therefore, the carton-feed operation is as follows:

Conveyor 26 carrying cartons to the apparatus urges them against the stationary detents 27, 27A where they remain until a pusher bar, say the bar 28, lifts the carton, say the carton 30, over the detents as shown in dotted lines of Fig. 1. The pusher bar 28 which lifts the carton 30 over the detents, proceeds past the carton to engage a preceding carton in the manner to be described. Having been lifted over the detent, carton 30 is urged onto conveyor 12 by the action of conveyor 26 and spaced rubber covered friction rolls 11A, 11B mounted on the sprocket shaft 13A. The rolls 11A, 11B are of somewhat larger diameter than the diameter of the chains 12A, 12B traveling over the sprockets 13. The carton thus carried onto conveyor 12 is stopped by the spring detent 32. The pusher bar 28A following behind the pusher bar 28 lifts a succeeding carton (not shown) over the stationary detents 27, 27A and passes under the succeeding carton to engage against the carton 30 retained in the conveyor by spring detent 32, forcing it past the spring detent and on down the conveyor.

The first stage in the opening operation involves opening the side flaps of the carton. These flaps being folded inwardly from the sides which lie in a plane parallel to the direction of travel of conveyor 12. In conventional apparatus for opening side flaps of cartons, plows have been used to engage under the inwardly folded flap, lifting it upwardly and outwardly away from the carton as the carton is caused to travel past the plow.

We have made an improvement on this presently existing apparatus which makes its operation considerably more positive. This improvement comprises means for exerting a constricting force momentarily on the sides of the carton below the flaps so as to spring the flaps upwardly where they are more readily engaged by succeeding plows. Constriction of the carton sides furnishes a positive means of partially opening the flaps and has an important advantage in that the engaging tips of the plows can be spaced well above the carton so that there is no danger of the plows interfering with cartons traveling on the conveyor. This arrangement comprises a pair of rollers 34, 34A mounted to rotate on a vertical axis adjacent the sides of the conveyor 12 and some distance above the conveyor and normally spaced outwardly from the sides of any cartons traveling along the conveyor. The rollers 34, 34A are rotatably mounted on rocker arms 35, 35A, respectively, which are spring loaded with springs 36, 36A to urge them away from the sides of the conveyor.

A pair of identical cylindrical cams 40, 40A are mounted on a shaft 41 rotatably mounted beneath the conveyor and journaled in opposite sides of framework 10. Shaft 13A, supporting sprocket 13 of conveyor 12 carries a sprocket 42 and a sprocket 43 is mounted on shaft 41 in alignment with the sprocket 42. A chain 44 carried over the sprockets 42, 43 drives the shaft

41 responsive to rotation of the shaft 13 to rotate the cylindrical cams 40, 40A.

Operation of the compression rollers 34, 34A responsive to rotation of cams driven from the conveyor sprocket shaft synchronizes movement of the rollers with the travel of conveyor 12.

The compression rollers 34, 34A are connected to be actuated by rotation of cams 40, 40A by means of a safety release mechanism shown in sectional elevation in Fig. 2A which is taken on line 2A—2A of Fig. 2, and in end elevation in Fig. 3. A rocker arm 46 is rotatably mounted at one end to a pillow block 46A stationarily mounted to the framework 10. A roller 47 is mounted to the opposite end of arm 46 to rotate on a vertical axis and to ride on the cammed surface of the cylindrical cam 40. Compression roller 34 is mounted on the rocker arm 35 to rotate on a vertical axis and to press against the sides of the cartons as described. The rocker arms 35 and 46 are joined to each other in pivotal relationship at a point spaced from their ends with a pivot pin 48. The pivot pin is spring loaded with the spring 36 to urge roller 34 outwardly from conveyor 12. Rocker arm 46 is provided with an upright ear 46B against which the end of rocker arm 35 abuts. A pin 49 is slidably journaled through the ear 46B and the abutting end of arm 35 and is cleated against the arm 35. A helical spring 49A is held under compression on the opposite end of pin 49 urging the end of rocker arm 35 against the ear 46B.

The operation of the cylindrical cams and the conveyor 12 is synchronized so that the compression rollers 34, 34A are normally urged inwardly to compress the sides of a carton, as for example, carton 50 in Fig. 3, between the centrally disposed rows of cans 51. Under normal circumstances, when the inward travel of rollers 34, 34A is not impeded by other than the carton sides, the rocker arms 36, 46 pivot together about the pivotal axis of arm 46. If, however, the machine should become jammed or synchronization between cams 40, 40A and conveyor 12 should be disturbed so that rollers 34, 34A are urged inwardly against the carton sides in line with a can row instead of between can rows, arms 35A and 46 will pivot with respect to each other about the pin 48. Spring 49A will absorb the difference in rotary movement under such circumstances. In this manner the apparatus will not be damaged nor will the contents of the misaligned carton.

The constriction of the carton sides produced by normal operation of the compression rollers between adjoining centrally disposed rows of cans, springs the side flaps 50A, 50B of carton 50 (Fig. 3) upwardly from the top of the carton. The end flaps 51A, 51B remain undisturbed.

A pair of plows 54, 54A are mounted above and to the sides of conveyor 12 with the ends of the plows projecting inwardly above the upper edges of cartons traveling on the conveyor to engage the sprung flaps of the cartons. Movement of a carton on the conveyor 12 with relation to the plows 54, 54A spreads the side flaps until they are bent outwardly and downwardly to engage against and be held in this position by the sides 56A, 56B of a channel member 56 in which the chains 12A, 12B travel (Fig. 4).

Contact switches 58, 58A are mounted on the plows 54, 54A, respectively, and a third contact switch 59 is mounted beneath the conveyor extending upwardly from channel 56. Switch 59 is actuated by the weight of cartons passing along 75

the conveyor. The three switches 58, 58A, 59 are connected in a circuit including the prime mover 15 to stop the machine unless both or neither of the plow switches 58, 58A are engaged. Thus, if for any reason only one of the side flaps of any carton is opened and in engagement with one of the plows, the machine will automatically stop itself to permit remedial measures to be taken. If both side flaps, however, are properly sprung to engage the plows, the operation of the machine will be continuous.

Having successfully opened the side flaps of the carton, it next becomes necessary, prior to removal of the cans from the carton, to open the end flaps. Heretofore this has been accomplished in apparatus designed for other purposes by changing the direction of travel of the carton or by rotating the carton through a 90° angle so that the end flaps are located adjacent the sides of the conveyor with the side flaps transverse to the conveyor. The present apparatus, on the other hand, provides means for opening the end flaps without disturbing the direction of travel or the orientation of the carton with respect to the single conveyor.

The end flap opening mechanism is shown in plan view in Fig. 2, sectional elevation in Fig. 1 and in transverse section in Fig. 4. Details of the operation of this device showing the relationship of the timing means to the flap opening means are shown in Figs. 5 and 6 and Figs. 7 and 8, respectively.

Arms 62, 63 are suspended across and above conveyor 12 and are rotatably mounted at each end to chain conveyors 64, 66. Chain 66 is carried over sprockets 67, 68 journaled inwardly from the framework 10, and chain 64 is carried over a like pair of sprockets journaled inwardly from the opposite side of the framework. One sprocket 40 of each pair is aligned coaxially with a sprocket 35 of the other pair so that the chains 64, 66 travel in identical loops carrying arms 62, 63 above the conveyor with one arm moving in the same direction as the conveyor while the other arm is moving in the opposite direction above the first arm. One sprocket of each pair is driven from a drive shaft 70, the other sprocket of each pair serving as an idler. Drive shaft 70 carries a pair of spaced sprockets 74, 91 which are connected to drive the drive sprocket of each of the above-mentioned pairs of sprockets. This arrangement is illustrated in the transverse sectional elevation of Fig. 4. Sprocket 67 carries a coaxial spur gear 78 and a second spur gear 75 is rotatably mounted in engagement with the spur gear 78. A sprocket 76 is mounted coaxially to the spur gear 75 and a chain 71 is carried over this sprocket and sprocket 74 on drive shaft 70. The spur gears 75, 78 are the same size and serve merely as reversing gears. The same type of arrangement is used to drive one of the sprockets carrying chain 64 from sprocket 91 mounted on drive shaft 70.

Each of the transverse arms 62, 63 carries a spaced pair of projecting fingers 82, 82A and 83, 83A, respectively, and a dog 84, 85, respectively. The several fingers project outwardly from the arms to lie in the part of a carton on conveyor 12 and are aligned to pass between the can rows when extending into the carton. The dog 84 projects outwardly from arm 62 and the dog 85 projects inwardly from arm 63, the two dogs serving to determine the angular orientation of the fingers as hereinafter described. A stationary cam 88 is mounted in the path of

travel of dog 84 so as to cause rotation of the arm 63 and hence, of the projecting fingers when the dog strikes the leading slanting edge 88A of the cam, the rotation being counter to the direction of travel of the finger. A second stationary cam 89 is mounted in the path of dog 84 causing rotation of arm 63 when the dog strikes the cam as will be more particularly described with relation to Figs. 5-8.

Drive shaft 70 not only drives the arms 62, 63 through suitable sprocket and spur gear arrangements as described but also controls the sequence of intermittent motion of the arms. A sleeve or hub 73 is rotatably mounted on the shaft 70. The hub carries a sprocket 71 and a friction or clutch plate 90. A second clutch plate 92 is mounted to or formed integrally with sprocket 91 previously described as forming a companion sprocket with sprocket 74. The hub 73 is spring loaded by means of a coil spring 93 mounted around shaft 70 and confined between an annular shoulder 70A and the hub. The spring 93 urges the clutch plates 90, 92 together so that under normal load conditions rotary motion is transmitted from sprocket 71 through the clutch to sprocket 91 and the shaft 70 to which the sprocket 91 is rigidly affixed. Sprocket 71 is driven by a chain 72 carried over a sprocket 14C (Fig. 2) on the sprocket shaft 14A.

Sprocket 91 serves the double function of driving chain 64 and as a timing gear to synchronize the movement of arms 62, 63 with the movement of cartons on conveyor 12. A plurality of studs 94, 94A, etc., project axially from the sprocket 91 adjacent its periphery and on the side opposite the clutch plate 92. A spring loaded pivotal latch 95 is normally disposed in the path of the studs. As described above, power transmission to the shaft 70 is through the sprocket 71, clutch plates 90, 92 and sprocket 91. When one of the studs 94, 94A abuts against the latch 95, the sprocket 91 is stopped, stopping the drive shaft 70. Under this condition rotation of sprocket 71 is dissipated by slippage between the clutch plates. When the drive shaft 70 does not rotate, the arms 62, 63 remain stationary.

Latch 95 is pivotally mounted intermediate its ends to a pillow block 95A projecting inwardly from side 10B of the framework (Figs. 2 and 4). A helical spring 95B is mounted on one end of the latch pivot pin, one end of the spring being anchored to the pin and the other end of the spring being anchored to the latch. Tension of the spring is such as to urge the end 99 (Figs. 6 and 8) of the latch into the path of the studs 94, etc. A stop 100 is rigidly mounted above the opposite end of the latch to limit latch rotation in a clockwise direction as viewed in Figs. 6 and 8, i. e., to limit the rotation of end 99 of the latch toward the axis of sprocket 91.

A floating sprocket 96 is rotatably mounted on the drive shaft 70 adjacent sprocket 91 and on the side opposite the clutch plate 92. The floating sprocket is driven by a chain 97 carried over a sprocket 14D on the sprocket shaft 14A. The floating sprocket 96 is provided with a plurality of studs 98, 98A extending axially toward the sprocket 91 and located adjacent the periphery of the sprocket on a somewhat shorter radius than the studs 94 on the sprocket 91. The lower portion 99A of the leading edge 99 of latch 95 is tapered in the direction of rotation of the sprockets. The tapered portion of the latch lies in the path of the studs 98, 98A, etc., when the latch is in its rest position determined by the

stop 100. When the sprocket 91 rotates to a point where one of the studs 94, etc., strikes the blunt edge of the latch, rotation of the sprocket is stopped. Sprocket 91 remains motionless until one of the studs 98 etc. on sprocket 96 strikes the tapered lower portion 99A of the leading edge 99 of the latch. When this happens the latch is deflected by continuing rotation of sprocket 96 to the point where the abutting stud 94 etc. bears against the tapered edge 99A to further deflect the latch. Sprocket 91 will again be free to rotate carrying stud 94 past the deflected latch. When the stud passes the latch, the latter returns to its rest position and will again stop the rotation of the sprocket 91 when a succeeding one of the studs 94, etc., strikes the latch.

The operation of the end flap opening mechanism is as follows and is shown in two stages of its operation in Figs. 5 and 6 and Figs. 7 and 8, respectively. The leading end flap 102A is opened first with the fingers 83, 83A pivoted forwardly as shown in Figs. 1 and 5, while the chains 64, 66 are being driven faster than carton 102 on conveyor 12. In this manner, the fingers 83, 83A engage under and lift the end flap 102A of the carton, say carton 102 (Figs. 1, 4 and 5) pivoting it upwardly and forwardly so that by the time the fingers 83, 83A have finished their forward motion and commence to travel on the radius of sprocket 67, the end flap 102A is bent outwardly from the leading end of the carton.

This position of the mechanism is shown in Fig. 5 and Fig. 6, the latter figure showing the timing sprocket 91 and the relationship of the studs 94, 94A thereon with respect to the latch 95. It will be seen from Fig. 5 that the finger 83A has carried the flap 102A from the position shown in Fig. 1 through an arc of approximately 180° so that it projects forwardly from the moving carton. As the finger 83A is carried upwardly on the radius of sprocket 67, the flap 102A springs upwardly engaging under belt 108 hereinafter described. The chain continues to travel, carrying the fingers 83, 83A around sprocket 67, at the same time the fingers 82, 82A are circumscribing the sprocket 68.

As the finger 82A (Fig. 5) reverses its direction around the sprocket 68, i. e., commences to travel in the direction of the cartons on conveyor 12, the dog 84, projecting outwardly from the arm 62 (Fig. 4), strikes the upper flat surface of the stationary cam 89, pivoting the fingers 82, 82A so that they lie substantially in the plane of travel of arm 62. While in this position, the two fingers are carried across the top of the carton 102 until they reach the inclined end face 89A of cam 89. By the time the fingers have reached the end of the cam 89, they have overtaken and passed a portion of the carton, including the trailing end flap 102B. As the dog 84 (Fig. 4) travels down the inclined face 89A of the cam, as shown in Fig. 7, pin 94 on timing sprocket 91 strikes the latch 95 (Fig. 8), stopping the motion of the arms 62, 63 and hence, of the fingers 82, 82A so that the end flap 102B (Fig. 7) catches on the fingers 82, 82A and swings through an arc of approximately 180° as the carton 102 is carried on conveyor 12 beneath the fingers 82, 82A. When the flap 102B has been partially elevated by the fingers 82, 82A, the stud 98A projecting from the floating sprocket 96 (Fig. 4) strikes the lower inclined edge 99A to pass beneath the latch. Motion of the chains 64, 66 is again instituted through clutch 87 carrying the fingers 82, 82A part way around the sprocket

67 to permit the carton 102 to pass beneath the fingers. Throughout this sequence of operations, the trailing end flap 102B is slowly swinging in an arc of 180° to extend outwardly from the trailing end of the carton.

As the arm 62 travels over the sprocket 61, the stud 94A on the timing sprocket 91 hits the latch 95, stopping the mechanism long enough to permit another carton to travel into the approximate position of the carton 102 in Fig. 1. Timed with the arrival of a succeeding carton, stud 98A on the floating sprocket 96 lifts latch 95, whereby sprocket 91 is again rotated through clutch 87 (Fig. 4), stud 94A passing under the latch 95. The cycle is thus complete and fingers 83, 83A are ready to engage under the leading end flap of a succeeding carton.

With the side flaps and end flaps of the carton open, the cans are removed from the carton. To accomplish this, a magnet 106, which may be either a permanent magnet or an electromagnet, is stationarily mounted above the end of conveyor 12 with one end of the magnet projecting a short distance over the end of the conveyor. A belt 108 is mounted around rollers 109, 110, etc., and extends across the under face of magnet 106. An idler roller 112 is spring loaded by an anchored spring 118 to maintain a uniform tension on belt 108. The belt is driven by the rubber surfaced compression rolls 20C and 114 between which it is threaded. In this manner, belt 108 travels continuously across the lower face of magnet 106. A belt conveyor 116 is extended beneath an end of the magnet opposite the conveyor 12 and is driven by a chain 117 carried over a sprocket 14E on shaft 14A and a sprocket (not shown) on pulley shaft 115A of the conveyor 116. A conveyor 120 is mounted beneath conveyors 12 and 116 spanning the gap between the adjacent ends of the upper conveyors. A chain 121 carried over a sprocket 14F on shaft 14A and a sprocket (not shown) on pulley shaft 120A of conveyor 120 drives the conveyor 120.

As an opened carton approaches the end of conveyor 12, the magnet 106 suspends cans 119 independently of the carton as succeeding rows of the cartoned cans come within the magnetic field. The cans are held against belt 108 and are carried across the under face of the magnet by the belt. As the belt carries the rows of cans across the face of the magnet toward the opposite edge, they are forced between conveyor 116 and belt 108 and are carried by the conveyor out of the magnetic field. The conveyor 116 discharges the cans at the lefthand end of the framework (as viewed in Fig. 1) and they are conveniently caused to fall from an upright position to a horizontal position into a slide or conveyor, not shown. The cartons discharged from the end of conveyor 12, and as the cans are retained on belt 108 by magnet 106, drop onto the conveyor 120. The cartons disposed on conveyor 120 may be discharged into a chute or another conveyor (not shown) and carried from there to any place in the plant for reloading with filled cans.

Although the invention has been described with relation to the removal of empty cans from an unsealed carton, it is not so limited and description of this particular type of operation was selected as representing a major industrial problem. The same apparatus can be used with equal success for removing filled cans or any type of metal container, either empty or full, from car-

tons in which the side and end flaps are free to fold away from the carton. If the cartons are received in a sealed condition, it is only necessary to break the seal, as with a knife, prior to feeding the cartons into the described apparatus.

Many modifications in the mechanical details of the apparatus of the invention will be apparent to any skilled engineer with particular reference to distribution of motive power, adjustment of various parts to accommodate cartons of different shapes and sizes, etc. Any modification in the apparatus wherein the same results are accomplished in substantially an equivalent manner, is included within the scope of the foregoing description and the following claims. An extensive discussion of the many modifications which could obviously be incorporated in the apparatus with respect to motivation; gearing, adjusting features, and the like, would serve no useful purpose.

We claim:

1. Apparatus for unloading containers from cartons having side flaps and end flaps comprising a conveyor, electrical motor means for operating said conveyor, means for spacing the cartons on the conveyor, means operable to successively fold the side flaps of each of the cartons outwardly from the sides of the carton, electrical contact means arranged serially with respect to said last named means for deenergizing said electrical motor means unless both side flaps of each carton are opened and engaging the electrical contact means, separate means for folding the end flaps of each carton outwardly from the carton, and means for suspending the cans independent of the carton and depositing them outside the carton, all of said means being arranged to operate in sequence on the separate cartons as they are carried by said conveyor.

2. Apparatus for removing metallic containers from cartons having side and end cover flaps comprising a first conveyor for the cartons, movable means disposed on opposite sides of the conveyor operably responsive to movement of the conveyor to depress the opposite sides of a carton on the conveyor to spring said side flaps upwardly, a pair of plows stationarily mounted above said conveyor serially with respect to said movable means to engage under said side flaps and fold them outwardly from the carton as the carton passes the plows, a second conveyor mounted above the first conveyor serially with respect to the plows, spaced fingers mounted to the second conveyor to alternately depend in the path of a carton travelling on the first conveyor, means for pivoting said fingers as they are moved by the second conveyor to cause a finger to engage under the flap on the leading end of the carton and fold it forwardly with respect to the carton, and to cause a different finger to sequentially engage under and fold the flap on the trailing end of the carton backwardly with respect to the carton, and magnetic means mounted adjacent the end of the first conveyor to suspend the containers independent of the opened cartons.

3. Apparatus for removing metallic containers from cartons having side and end cover flaps comprising a first conveyor for the cartons, movable means disposed on opposite sides of the conveyor operably responsive to movement of the conveyor to depress the opposite sides of a carton on the conveyor to spring said side flaps upwardly, a pair of plows stationarily mounted above said conveyor serially with respect to said

movable means to engage under said side flaps and fold them outwardly from the carton as the carton passes the plows, a second conveyor mounted above the first conveyor serially with respect to the plows, spaced fingers mounted to the second conveyor to alternately depend in the path of a carton travelling on the first conveyor, means for pivoting said fingers as they are moved by the second conveyor to cause a finger to engage under the flap on the leading end of the carton and fold it forwardly with respect to the carton, and to cause a different finger to sequentially engage under and fold the flap on the trailing end of the carton backwardly with respect to the carton, a magnet mounted adjacent and above the discharge end of the first conveyor and extending beyond the end of the conveyor, and a third conveyor travelling across the lower face of the magnet.

4. Apparatus for removing metallic containers from cartons having side and end cover flaps comprising a first conveyor for the cartons, movable means disposed on opposite sides of the conveyor operably responsive to movement of the conveyor to depress the opposite sides of a carton on the conveyor to spring said side flaps upwardly, a pair of plows stationarily mounted above said conveyor serially with respect to said movable means to engage under said side flaps and fold them outwardly from the carton as the carton passes the plows, a second conveyor mounted above the first conveyor serially with respect to the plows, spaced fingers mounted to the second conveyor to alternately depend in the path of a carton travelling on the first conveyor, means for automatically starting and stopping the second conveyor said means being synchronized with the carton spacing on said first conveyor, means for pivoting said fingers as they are moved by the second conveyor to cause a finger to engage under the flap on the leading end of the carton and fold it forwardly with respect to the carton, and to cause a different finger to sequentially engage under and fold the flap on the trailing end of the carton backwardly with respect to the carton, a magnet mounted adjacent and above the discharge end of the first conveyor and extending beyond the end of the conveyor, and a third conveyor travelling across the lower face of the magnet.

5. Apparatus for removing metallic containers from cartons having side and end cover flaps comprising a first conveyor for the cartons, means for equally spacing succeeding cartons on the conveyor, movable means disposed on opposite sides of the conveyor, and operable responsive to movement of the conveyor to depress the opposite sides of a carton on the conveyor to spring said side flaps upwardly, a pair of plows stationarily mounted above said conveyor serially with respect to said movable means to engage under said side flaps and fold them outwardly from the carton as the carton passes the plows, a second conveyor mounted above the first conveyor serially with respect to the plows, spaced fingers mounted to the second conveyor to alternately depend in the path of a carton travelling on the first conveyor, means for automatically starting and stopping the second conveyor synchronized with the carton spacing on said first conveyor, means for pivoting said fingers as they are moved by the second conveyor to cause a first finger to engage under the flap on the leading end of the carton and fold it forwardly with respect to the carton, and to cause a different finger

to sequentially engage under and fold the flap on the trailing end of the carton backwardly with respect to the carton, a magnet mounted adjacent and above the discharge end of the first conveyor and extending beyond the end of the conveyor, a third conveyor travelling across the lower face of the magnet.

6. Apparatus for removing metallic containers from cartons having side and end cover flaps comprising a first conveyor for the cartons, means for equally spacing succeeding cartons on the conveyor, separate movable means disposed on opposite sides of the conveyor operably responsive to movement of the conveyor to depress the opposite sides of a carton on the conveyor to spring said side flaps upwardly, a pair of plows stationarily mounted above said conveyor serially with respect to said movable means to engage under said side flaps and fold them outwardly from the carton as the carton passes the plows, switch means connected to stop said first conveyor when only one of said plows is in contact with a side flap, a second conveyor mounted above the first conveyor serially with respect to the plows, spaced fingers mounted to the second conveyor to alternately depend in the path of a carton travelling on the first conveyor, means for automatically starting and stopping the second conveyor synchronized with the carton spacing on said first conveyor, means for pivoting said fingers as they are moved by the second conveyor to cause a finger to engage under the flap on the leading end of the carton and fold it forwardly with respect to the carton, and to cause a different finger to sequentially engage under and fold the flap on the trailing end of the carton backwardly with respect to the carton, a magnet mounted adjacent and above the discharge end of the first conveyor and extending beyond the end of the conveyor, and a third conveyor travelling across the lower face of the magnet.

7. Apparatus according to claim 6 wherein each of said separate movable means operable to depress the sides of a carton in the first conveyor comprises a first roller mounted to rotate about a vertical axis on a first loaded pivot arm, a second pivot arm pivotally mounted to the first arm, a second roller mounted to rotate about a vertical axis on said second pivot arm, a cylindrical cam mounted on a horizontal rotatable shaft so that said second roller rides on the cammed surface, means for rotating said shaft, and releasable means for preventing relative rotation of said first and second pivot arms.

8. Apparatus according to claim 7 wherein, the cylindrical cams for each of the separate movable means are mounted on the same shaft and are of identical shape whereby the movement of each of said first rollers is synchronized.

9. Apparatus according to claim 6 wherein said second conveyor comprises a pair of synchronously driven chain conveyors spaced above and adjacent the opposite sides of said second conveyor, a pair of travelling arms connected at opposite ends to the pair of conveyors and spaced from each other along the pair of conveyors, said spaced fingers being mounted to said travelling arms.

10. Apparatus according to claim 9 wherein said travelling arms are rotatably connected to said pair of conveyors and said means for pivoting said fingers comprises a pair of stationary cams mounted adjacent one of said pair of conveyors, and a separate clog mounted to each travelling arm and projecting therefrom to en-

gage one of said cams to rotate the respective travelling arm as the conveyor carries the clog against the cam.

11. Apparatus according to claim 6 wherein the second conveyor is driven from a single drive shaft, and the means for automatically stopping said second conveyor comprises a first sprocket mounted on a hub rotatable on said drive shaft, a chain connecting said first sprocket to be rotated responsive to movement of the first conveyor, a first clutch plate formed on an end of said hub, a second sprocket rigidly mounted on said shaft, a second clutch plate mounted on said second sprocket, spring means urging said first and second clutch plates together so that rotation of said first sprocket is transmitted through said clutch plates and second sprocket to said shaft, a plurality of studs mounted to and projecting axially from said second sprocket, a third sprocket rotatably mounted on said shaft, a chain connecting said third sprocket to be rotated, responsive to movement of said first conveyor, independently of said first sprocket and said shaft, a plurality of studs mounted to and projecting axially from said third sprocket, a spring loaded stop mounted to rest in the path of the studs on the second and third sprockets so that rotation of the second sprocket is stopped when one of its studs strikes the latch, and the latch is deflected to permit passage of said one of said studs when a stud on the third sprocket strikes the latch.

12. In apparatus for opening a carton containing a series of rows of containers and having side flaps folded inwardly from its sides, the combination comprising a conveyor for the carton, movable means disposed on opposite sides of the conveyor outwardly of the path of cartons traveling on the conveyor, means operable intermittently and responsive to movement of the conveyor to simultaneously displace the movable means inwardly to exert a squeezing force on the sides of the carton below said side flaps and between adjoining rows of containers whereby the side flaps are partially opened, and a pair of plows mounted above and to the sides of the conveyor serially with respect said movable means to engage under each of the partially opened side flaps as the carton travels on the conveyor and to bend the side flaps outwardly of the carton under the influence of the motion of the carton.

13. In apparatus for opening a carton having side flaps folded inwardly from its sides, the combination comprising a conveyor for the carton, movable means disposed on opposite sides of the conveyor and operable simultaneously to exert a squeezing force on the sides of the carton below said side flaps whereby the side flaps are partially opened, a pair of plows mounted above and to the sides of the conveyor serially with respect said movable means, to engage under each of the partially opened side flaps as the carton travels on the conveyor and to bend the side flaps outwardly of the carton under the influence of the motion of the carton, and a separate contact switch mounted on each of the plows and on the conveyor and connected to stop the conveyor when at least one and less than all of the switches are contacted.

14. In apparatus for opening a carton having side flaps folded inwardly from its sides, the combination comprising a conveyor for the carton, movable means disposed on opposite sides of the conveyor and operable simultaneously to exert a squeezing force on the sides of the carton below said side flaps whereby the side flaps are partially opened and a pair of plows mounted above

and to the side of the conveyor serially with respect said movable means to engage under each of the partially opened side flaps as the carton travels on the conveyor and to bend the side flaps outwardly from the carton under the influence of the motion of the carton, and means for automatically releasing the movable means to prevent said squeezing force responsive to abnormal resistance to said squeezing force.

15. In apparatus for opening the end flaps of a carton, the combination comprising a conveyor for the carton, a second conveyor disposed above a portion of the first conveyor and travelling oppositely to the first conveyor so that the adjacent surfaces travel in the same direction, spaced fingers mounted to said second conveyor and projecting into the path of a carton travelling on said first conveyor, means for intermittently driving the second conveyor to cause a finger projecting therefrom to engage under the leading end flap and fold it forwardly away from the carton, means for stopping the second conveyor to cause a different one of said fingers to catch under the trailing end flap and fold it backwardly as the carton travels under said different one of said fingers.

16. In apparatus for opening the end flaps of a carton, the combination comprising a conveyor for the carton, a second conveyor disposed above a portion of the first conveyor and travelling oppositely to the first conveyor so that the adjacent surfaces travel in the same direction, a pair of transverse arms mounted to said second conveyor and spaced from each other, separate fingers mounted to said pair of arms and projecting into the path of a carton travelling on said first conveyor, means for intermittently driving the second conveyor to cause a finger projecting therefrom to engage under the leading end flap of the carton, and fold it forwardly away from the carton, means for stopping the second conveyor to cause a different one of said fingers to catch under the trailing end flap of the carton, and fold it backwardly as the carton travels under said different one of said fingers.

17. In apparatus for opening the end flaps of a carton, the combination comprising a first conveyor for the carton, a second conveyor disposed above a portion of the first conveyor and travelling oppositely to the first conveyor so that the adjacent surfaces travel in the same direction, a pair of transverse arms mounted to said second conveyor to rotate in a horizontal axis, separate fingers mounted to each of said arms, means for intermittently driving the second conveyor to cause a finger projecting therefrom to engage under the leading end flap and fold it forwardly away from the carton, means for stopping the second conveyor to cause a different one of said fingers to catch under the trailing end flap and fold it backwardly as the carton travels under said different one of said fingers, and means for rotating said arms at given points in the travel of said second conveyor to pivot said fingers into a position to engage said flaps.

18. In apparatus for opening the end flaps of a carton, the combination comprising a first conveyor for the carton, a second conveyor disposed above a portion of the first conveyor and travelling oppositely to the first conveyor so that the adjacent surfaces travel in the same direction, a pair of arms rotatably mounted to said second conveyor transversely to said first conveyor, a pair of spaced fingers mounted to each of said arms, means for intermittently driving the sec-

ond conveyor to cause a finger projecting therefrom to engage under the leading end flap and fold it forwardly away from the carton, means for stopping the second conveyor to cause a different one of said fingers to catch under the trailing end flap and fold it backwardly as the carton travels under said different one of said fingers, the means for driving and stopping the second conveyor being synchronized with the first conveyor, and means for rotating said arms at given points in the travel of said second conveyor to separately pivot the pairs of fingers.

19. Apparatus for unloading metal containers from cartons comprising magnetic means having an underface, an upper conveyor travelling across said underface of said magnetic means, a lower delivery conveyor for feeding the cartons having its discharge end projecting a distance under said magnetic means, said magnetic means being spaced above said discharge end of said delivery conveyor a distance sufficient to lift the containers off the bottom of the cartons and cause suspension of the containers within the cartons to insure positive removal of the containers, and a discharge conveyor for receiving containers from said upper conveyor and having its receiving end projecting a distance under said magnetic means and being spaced from the discharge end of the delivery conveyor a distance sufficient to enable downward removal therebetween of the cartons, said magnetic means being spaced above the receiving end of said discharge conveyor a distance substantially equal to the height of the containers to cause forced delivery of the containers into the space between the magnetic means and the discharge conveyor to maintain proper alignment of the containers while being removed from the magnetic means.

20. An apparatus in accordance with claim 19 and including means for opening cartons, having side flaps and end flaps, while on said delivery conveyor, said means having first means operable to successively fold the side flaps of each of the

cartons outwardly from the sides of the carton, and second means for successively folding the end flaps of each of the cartons outwardly from the carton.

- 5 21. In apparatus for opening a carton having side flaps folded inwardly from its sides, the combination comprising a conveyor for the carton, a first pair of rollers mounted on opposite sides of the conveyor, each roller being mounted to rotate about a vertical axis on a first pivot arm, a second pivot arm pivotally mounted to each of the first arms and including a projection preventing relative rotation of the respective one of said first arms in one direction, spring means connected to impede relative rotation of the first arms in the opposite direction, a second roller mounted to each of the second arms, a pair of cams rotatable responsive to movement of the conveyor and respectively contacting the second rollers so that rotation of the cams periodically urges the first rollers inwardly with respect to the conveyor to exert a squeezing force on the sides of the carton below said side flaps whereby the side flaps are partially open, and stationary means spaced from the first rollers to engage under each of the partially opened side flaps as the carton travels on the conveyor and to bend the side flaps outwardly of the carton under the influence of the motion of the carton.
